UNITED STATES PATENT OFFICE.

MICHAEL F. CAHILL, OF LYNCHBURG, VIRGINIA.

CROWBAR.

SPECIFICATION forming part of Letters Patent No. 727,284, dated May 5, 1903.

Application filed February 27, 1903. Serial No. 145,416. (No model.)

To all whom it may concern:

Be it known that I, MICHAEL F. CAHILL, a citizen of the United States, residing at Lynchburg, in the county of Campbell and State of Virginia, have invented new and useful Improvements in Crowbars, of which the following is a specification.

My invention relates to new and useful improvements in crowbars; and its object is to provide an attachment which is adjustably secured thereto and which is so constructed as to readily engage a timber or other similar article placed thereunder and serve as a fulcrum for the bar.

15 The invention consists in providing a crowbar having a series of apertures therein, one of which is adapted to receive a pin which extends through the forked end of a plate which is provided with sharpened lugs or projections at the opposite end.

20 The invention also consists in the further novel construction and combination of parts hereinafter more fully described and claimed, and illustrated in the accompanying drawings, showing the preferred form of my invention, and in which—

25 Figure 1 is a perspective view of the device. Fig. 2 is a section therethrough. Fig. 3 is an end elevation, and Figs. 4 and 5 are 30 detail views showing the manner in which said bar may be employed.

Referring to the figures by numerals of reference, 1 is a crowbar preferably provided with a toe 2 at one end thereof and having a series of apertures 3. Any one of these apertures is adapted to receive a bolt or pin 4, which extends through ears 5, projecting from a head 6, which is formed at the upper end of a plate 7. The lower edge of the plate is 35 sharpened, as shown at 8, and the ends of said edge have pointed lugs or extensions 9 projecting therefrom. The movement of the plate in relation to the bar is limited by the head 6, which forms a bearing for the bar, as 40 illustrated in Fig. 2.

45 The device is especially adapted for use where it is ordinarily impossible to insert a block to be used as a fulcrum for the lever.

50 In Figs. 4 and 5 I have shown the device in use upon a railway-trestle. It will be seen

that as the plate 7 is but little wider than the bar 1 it can be readily inserted between ties 10 and placed in engagement with a cross-beam 11. By placing the toe 2 in engagement with the timbers 12 and drawing downward upon the bar in direction of the arrow in Fig. 4 said timbers can be forced upwardly and outwardly. The same result can be obtained by reversing the bar, so as to bring the toe in engagement with the beam 60 11 and placing the extensions 9 in engagement with the timbers 12. The bar 1 in this case can be drawn upward, as indicated by the arrow in Fig. 5. The attachment is extremely simple and inexpensive and can be 65 readily used in connection with an ordinary crowbar, provided apertures 3 are formed within the same. The leverage of the bar can be adjusted by removing the bolt 4 and placing it in a desired one of the apertures 3. 70

In the foregoing description I have shown the preferred form of my invention; but I do not limit myself thereto, as I am aware that modifications may be made therein without departing from the spirit or sacrificing any 75 of the advantages thereof, and I therefore reserve the right to make such changes as fairly fall within the scope of my invention.

Having thus described the invention, what is claimed as new is—

1. The combination with a bar having apertures therein; of a plate, ears at one end thereof adapted to receive the bar therebetween, and extensions at the opposite end of the plate. 85

2. The combination with a bar having apertures therein; of a plate, parallel ears at one end thereof adapted to be pivoted to opposite sides of the bar, and pointed extensions at the opposite end of the plate. 90

3. The combination with a bar having a toe at one end, and a series of apertures; of a plate, a head at one end thereof, ears projecting from the head extending to opposite sides of the bar, a pivoted bolt within the ears and engaging one of the apertures, and extensions at the opposite end of the plate. 95

4. The combination with a bar having a toe at one end, and a series of apertures; of a plate, a head at one end thereof, parallel ears 100

extending from the head to opposite sides of the bar, a bolt secured to the ears and engaging one of said apertures, a sharpened working edge to the plate, and pointed extensions at the ends of said edge.

5. A crowbar attachment of the character described comprising a plate having a sharpened working edge, pointed extensions at the ends of said edge, a head at the opposite end

of the plate, parallel ears extending therefrom, and a pivot-bolt connecting the ears.

In testimony whereof I affix my signature in presence of two witnesses.

MICHAEL F. CAHILL.
